[57] CLAIM

The ornamental design for apparatus for dispensing drinks, as shown and described.

DESCRIPTION

FIG. 1 is a front elevation of an apparatus for dispensing drinks showing my new design;
FIG. 2 is a left-side elevation thereof;
FIG. 3 is a right-side elevation thereof;
FIG. 4 is a rear elevation thereof;
FIG. 5 is a top view thereof;
FIG. 6 is a bottom view thereof;
FIG. 7 is a perspective view thereof;
FIG. 8 is a front elevational view showing a second embodiment of my new design;
FIG. 9 is a left side elevational view thereof;
FIG. 10 is a right side elevational view thereof;
FIG. 11 is a rear elevational view thereof;
FIG. 12 is a top plan view thereof;
FIG. 13 is a bottom plan view thereof;
FIG. 14 is a perspective view thereof;
FIG. 15 is a front elevational view showing a third embodiment of my new design;
FIG. 16 is a left side elevational view thereof;
FIG. 17 is a right side elevational view thereof;
FIG. 18 is a rear elevational view thereof;
FIG. 19 is a top plan view thereof;
FIG. 20 is a bottom plan view thereof; and,
FIG. 21 is a perspective view thereof.
